CLAIM

The ornamental design for a massage shower, as shown
and described.

DESCRIPTION

FIG. 1 is a front perspective view of a massage shower
showing my new design;

FIG. 2 is a top plan view thereof;

FIG. 3 is a bottom plan view thereof;

FIG. 4 is a side elevational view thereof, the other side
being a mirror image thereof;

FIG. 5 is a front elevational view thereof; and

FIG. 6 is a rear elevational view thereof.
